BOAT PROPELLING MECHANISM

Philip O'Dwyer, Detroit, Mich.

Application November 2, 1938, Serial No. 238,460

Renewed February 23, 1940

1 Claim. (Cl. 115—24)

My invention relates to a new and useful improvement in a boat propelling mechanism adapted for use in propelling a boat through the water and manually operable, the propelling mechanism being operated by the occupants of the boat. The invention lends itself to the type of boat commonly referred to as a rowboat regardless as to whether it is of the small type propelled by one rower or of the larger type in which a large number of rowers are engaged in the propelling action.

It is an object of the present invention to provide a mechanism whereby a rockable lever may be used through cooperation with reciprocating members for transmitting a rotary motion to a shaft geared for rotating a screw propeller and in which a maximum efficiency may be obtained.

It is another object of the invention to provide a mechanism of this type in which the rockable lever may be connected by a dual connection to a crankshaft so that the lever mounted pivotally between its ends may serve effectively to rotate the crankshaft both through the upper portion and lower portion of the lever.

Experience has shown that in devices of this kind with a dual connection to a crankshaft and particularly where the reciprocating rods are positioned substantially in alignment one above the other, a locking of the crankshaft against rotation is effected and in order to overcome this it is necessary that a floating shaft be provided for the rockable lever and this I have accomplished by a mechanism in which the lever is pivotally mounted for a more efficient operation.

Another object of the invention is the provision of a boat propelling mechanism which will be simple in structure, economical of manufacture, compact, durable and easily operated and installed.

Other objects will appear hereinafter.

The invention consists in the combination and arrangement of parts hereinafter described and claimed.

The invention will be best understood by a reference to the accompanying drawing which forms a part of this specification, and in which Fig. 1 is a fragmentary top plan view of a boat showing the invention applied with parts broken away.

Fig. 2 is a fragmentary, central, vertical, sectional view of the invention showing it applied to a boat.

Fig. 3 is a sectional view taken on line 3—3 of Fig. 2.

Fig. 4 is a fragmentary side elevational view of a modified form of the invention.

Fig. 5 is a fragmentary, sectional view taken on line 5—5 of Fig. 4.

In the drawing I have illustrated the invention applied to a boat 9 having a plurality of crossplates 10 which serve as seats for the occupants of the boat. Extending longitudinally 10 of the boat at substantially the lower medial line thereof and overlying and resting upon the plates 10 is an elongated plate 11 having slots 12 formed therein between each of the plates 10. Extending upwardly from the bottom 13 16 of the boat are spaced standards 14 and 15, these standards being positioned at opposite sides of each of the slots 12. Projected through each of the slots 12 is a rockable lever 16 which is pivoted intermediate its ends on a crank 17 20 formed on a rod 18 which is journaled in the openings 19 and 20 formed in the standards 14 and 15, respectively.

A screw propeller 21 is fixedly mounted on a shaft 22 which extends through the guide sleeve 23 into the interior of the boat and which carries on its inner end a bevel gear 24 adapted to mesh with a bevel gear 25 fixedly mounted on the shaft 26, this shaft 26 being journaled in the bearings 27 mounted on a suitable supporting structure in the boat. As shown in Fig. 1, I have provided a pair of these rods 22 each carrying its bevel gear meshing with the cooperating bevel gear 25. In the form shown in Fig. 1, I have formed a pair of cranks 28 and 29 in the shaft 26, these cranks being extended in opposite directions from each other so that they are spaced apart one hundred and eighty (180°) degrees. It is believed obvious that if it is desired to attach a pair of operating mechanisms for rotating the shaft 26, four of the cranks may be provided instead of the two cranks 28 and 29 which are illustrated in which event the cranks would be spaced apart circumferentially ninety (90°) degrees instead of one hundred and eighty (180°) degrees.

Pivots connecting at one of its ends to the crank 28 is a link 30, the opposite end of which is pivotally connected to the elongated rod 31. The other crank 29 is pivotally connected to 50 one end of a link 32, the opposite end of which is pivotally connected to the elongated rod 33 which is positioned substantially beneath the rod 31. The rod 31 is pivotally connected by means of the rivet 34 to each of the levers 16 55

above the point of the pivot of the lever 16. The rod 33 is similarly connected by means of the pin 35 to each of the levers 16 below the point of pivot. Extended through the upper end of 5 each of the levers 16 is a hand grip 36.

The construction is such that when the levers 16 are rocked on their pivots, the rods 31 and 33 are reciprocated to effect a rotation of the shaft 26 and thus serve to rotate the screw propellers 21 for propelling the boat. It will be noted that the rod 33 is connected to the lever 16 on the side opposite to that at which the rod 31 is connected so that while these rods are positioned in superimposed relation are laterally offset from each 15 other the width of the lever 16. When the levers 16 are rocked, the crank 17 also rocks as this motion is necessary in order to prevent a binding of the rods 31 and 33. Consequently, the levers 16 are pivotally mounted on a floating shaft and 20 each is pivotally connected above its point of pivot to one of the operating rods and below its point of pivot to the other operating rod.

In the form shown in Fig. 4 and Fig. 5, the rod 18' is a straight rod which serves as a pivot but 25 which projects at its opposite ends through elongated slots 19' formed in the standards 14 and 15. In this construction the floating mounting of the pivot is still present.

With a construction as illustrated, I have provided a box-like longitudinally extending structure which serves to reenforce the boat and which also serves as a means for enclosing the reciprocating rods 31 and 33 and serving as a guide therefor.

35 It is believed obvious that a person seated on the seat-forming plate 10 may easily operate the propelling mechanism regardless of the direction the operator is faced and that a maximum efficiency is obtained in the construction illustrated.

While I have illustrated and described the preferred form of construction, I do not wish to

limit myself to the precise details of structure shown, but desire to avail myself of such variations and modifications as may come within the scope of the appended claim.

What I claim as new is:

A device of the class described, adapted for use with a boat having a bottom and a plurality of transverse seats comprising: an elongated guide strip extending longitudinally of said boat centrally thereof, in engagement with said seats, and provided with a plurality of spaced elongated longitudinally extending slots; spaced standards projecting upwardly from the bottom of said boat, said standards having, at spaced intervals, between the upper and lower edges thereof, registering, longitudinally-directed, elongated slots; a plurality of levers each of said levers projecting at its upper end through a slot formed in said guide strip; a pin projecting through each of said levers intermediate its ends and engaging in registering slots in said standards, a crankshaft extending transversely of said boat adjacent one end and having a pair of cranks circumferentially relatively rotated; an operating rod extending longitudinally of said boat below said guide strip and above the point of pivot of said levers and between said standards pivotally connected to one side of each of said levers; means for connecting one end of said rod to one of the cranks of said shaft; a longitudinally extending operating rod extending below said guide strip and below the point of pivot of said levers and between said standards and pivotally connected to the opposite side of each of said levers below the point of pivot of 35 said levers; means for connecting said last-named rod to the other crank of said crankshaft for effecting, upon a rocking of said levers, a rotation of said crankshaft; and boat propelling means operable upon the rotation of said crankshaft.

PHILIP O'DWYER.
